UNITED STATES PATENT OFFICE.

THOMAS F. HILLIARD, OF OIL CITY, PENNSYLVANIA.

PORABLE MILLING-MACHINE FOR MILLING POCKETS FOR SWITCH-POINTS IN STOCK-RAILS.

1,138,656.

Specification of Letters Patent.

Patented May 11, 1915.

Application filed July 13, 1914. Serial No. 850,778.

To all whom it may concern:

Be it known that I, THOMAS F. HILLIARD, citizen of the United States, residing at Oil City, in the county of Venango and State of Pennsylvania, have invented certain new and useful Improvements in Portable Milling-Machines for Milling Pockets for Switch-Points in Stock-Rails, of which the following is a specification.

10 The object, construction and operation of my improved portable milling machine, are herein set forth with sufficient clearness to enable those skilled in the art to which it most nearly relates to make and use the 15 same.

Object.—The object of this invention is to provide a suitable machine for milling off the side of the ball or head of a railway-rail, such as is termed a "stock rail," after 20 it has been placed in the track, and at the particular location where a switch-point comes into contact with said rail-head, for the purpose of forming a wider, truer, firmer bearing and lateral support for said switch- 25 point, so that the same will be protected from the wear and pressure of the wheels of the rolling-stock, thus insuring greater durability of said point, and greater safety to the trains passing over same, and to the operatives of said trains and the passengers carried thereby.

Heretofore, the work which this machine is designed to perform, has been done with hammer and chisel, but this is not only a 35 laborious process, but the results obtained are not always satisfactory.

Construction.—The construction whereby I attain said objects, is clearly shown in the drawings, the various figures of which are 40 as follows:

Figure 1 is a right-side elevation of the machine, Fig. 2 is a plan view of same, Fig. 3 is a left-side elevation, Fig. 4 is an end view, Fig. 5 is a section on line V—V of 45 Fig. 2, Fig. 6 is a section on line VI—VI of Fig. 2, Figs. 7, 8 and 9 are details, Fig. 10 shows the head of a rail upon which is indicated by the section-lined portion, the part of the head which is to be removed by means 50 of my machine.

The same reference character is applied to identical parts in all the views.

As here illustrated, my milling machine 55 comprises a bed 1, provided at either end with suitable clamps 2, arranged to engage

the head or ball of a railway rail 3, and to clamp said bed firmly thereto, so that the machine cannot move, either laterally or longitudinally of the rail, nor sway thereon. At either end of said bed, and upon both 60 sides thereof, are formed downwardly-projecting lugs 4, 4, which are arranged to be positioned upon either side of the rail-head when the machine is in the operating position, as shown in Fig. 4. An adjusting 65 screw 5 projects through each of said lugs, the inner ends of which screws are arranged to bear against their respective side of the rail head for the purpose of securing the proper position and alinement of said bed 70 1 upon the rail, also for making lateral adjustments of said bed upon said rail before the clamps 2 have been tightened. By this means the depth of the cut of the milling-tool 6 into the rail may be varied, as desired. Said screws also adapt the machine 75 to be applied to rails of various sizes.

Fig. 10 is a full sized section of a rail weighing 100 pounds to the yard, and the portion which is cross-hatched shows substantially the amount which it is necessary 80 to remove to form the abutting surface for a switch-point.

Bed 1 is provided with a carriage-rail 7, and a carriage 8 is mounted thereon and 85 adapted to travel longitudinally thereof. The upper face of said rail 7 is provided with a rack 9. Mounted in proximity to one end of said carriage is a pinion 10,—Fig. 5,—which meshes with said rack 9, for the purpose hereinafter set forth.

Upon the outer end of the shaft 11 which carries said pinion 10, is loosely or revolubly mounted a worm-wheel 12, the hub of which is formed into one member 13 of a jaw-clutch; the other member 14 of said clutch is feathered upon the feed-shaft 11 and is adapted to be slipped into and out of engagement with its companion member 13, 95 whereby said feed-shaft 11 may be revolved by said worm-wheel, or said shaft may revolve without revolving said wheel, and the purpose of this arrangement will presently appear. Upon said carriage 8 is mounted a vertically-extending bracket 15, which is 100 provided with bearings 16 and 17 for the reception and mounting of a revoluble power-transmission shaft 18, to the upper end of which is keyed a bevel gear 19. At the upper end of said bracket 15, bearings 116

20, 20 are provided, and a horizontally-disposed, power-receiving shaft 21 is revolubly mounted in said bearings. A bevel pinion 22 is keyed to said shaft 21 and meshes with 5 the gear 19 for the purpose of driving same and shaft 18 to which it is secured. Said shaft 21 extends, at either end, beyond the bearings 20, and said extending ends are each adapted for the reception of an operating crank 23, whereby the machine is adapted to be manually operated. I do not wish, however, to be understood as confining my invention to a manually-operated machine, for the reason that a power-driven 10 machine is equally within the scope of my invention.

The lower end of shaft 18 terminates in the bearing 24, which bearing is carried by the carriage 8 and is an extension of the 20 bracket 15. Swingly mounted upon said shaft 18, and positioned between the bearings 16 and 24, is the milling-tool arm 25, which is shown removed from the machine and in side elevation in Fig. 7. Said arm is 25 provided with two bearings, an upper bearing 26 and a lower bearing 27, through which shaft 18 passes. Positioned between said bearings 26 and 27, mounted upon said shaft 18 and keyed thereto, is a worm 28 30 and a spur-gear 29. Said worm, meshes with and is adapted to drive said worm-wheel 12, and, through the medium of clutch members 13 and 14, previously described, to drive shaft 11 and the thereto-attached 35 pinion 10, whereby carriage 8 is caused to travel longitudinally of rail 7 and bed 1. When the machine is in operation, said carriage travels in the direction indicated by the arrows in Figs. 1, 2 and 9.

40 In the arm 25 is mounted an arbor 30,—see Fig. 6,—to the lower end of which is secured a milling-cutter 6. Keyed to said arbor is a pinion 31, to which motion is transmitted from pinion 29 through the medium of the intermediate pinion 32. Above the milling-cutter 6, is provided a sleeve 33 having a plain periphery, which is adapted to travel against or impinge upon the milling-guide 34, that is removably attached to 45 bed 1, and is separately shown in Fig. 9. The profile of the outer guide-face, against which sleeve 33 travels is formed to define or regulate the work of the cutter 6, both as to the depth of its cut and the longitudinal extent of same, and to define the point at which it will begin to cut and the point at which it will cease to cut, and this definition is automatically provided for and secured in the following manner: As previously 50 stated, arm 25 is swingingly mounted upon shaft 18, so that the cutter 6 is movable toward, or away from, its work,—that is, toward or away from the rail-head. Now, for the purpose of holding said cutter 55 yieldably, yet with sufficient pressure up to

its work to cause it to properly perform the same, I provide a bolt 35, which is attached at its inner end to the carriage 8.

The free, or outer end of arm 25 is provided with an eye 36, through which said bolt 35 passes; a spring 37 is provided which bears at its inner end against said arm, and through which spring said bolt also passes; a washer 38 is placed upon the end of said bolt 35, and, by means of a nut 39, said washer is caused to bear against the adjacent end of said spring 37, thus causing said spring, in turn, to bear against said arm with the proper amount of pressure to hold cutter 6 to its work. It will be readily understood that said pressure may be regulated as desired by means of said nut 39.

By reference to Fig. 9 it will be noticed that the ends of the guide 34 are thicker than the intermediate portion. Said thicker, 85 end portions are for the purpose of causing cutter 6 to move outwardly, away from the rail upon which it operates, thus automatically imparting to the milled pocket, or face of the rail, the proper length, profile 90 and area for the proper seating of a switch-point. I call attention to the fact that said area, the length, depth and profile of said switch-point pocket, thus milled, may be modified as desired by modifying the guide 95 face of the guide 34, which is made removable for the purpose of readily permitting said modification, and the use of guides of various shapes. Attention has already been called to the fact that the depth of said 100 pocket may also be modified by means of the lateral adjustments made possible by the screws 5.

In Fig. 8 is shown one of the clamps that are employed to clamp the bed of my machine to the railway-rail 3. For the reception of these clamps a slotted way is milled transversely of the bed 1, in which said clamps are inserted, and a right-and-left-hand screw 40 is employed to actuate each 105 pair of clamps. Face 41 of the clamp, which bears against the face 42 of the rail, conforms thereto, and when said screws 40 are turned so as to draw said clamps together into the rail-engaging or clamping position, 110 their action is such as to clamp the bed 1 firmly to the rail 3 of a railway track. This clamping construction is such that the machine may be quickly placed and clamped in position, also quickly unclamped and removed from the rail. Said quick removal is necessary for the reason that this machine must often be used on railway tracks, where trains are in operation, and the use of the machine must not interfere with the movement of such trains; in order to meet this requirement, the machine must be so constructed as to be quickly removable, to permit the passage of trains, also quickly replaceable, to avoid loss of time.

The machine, as shown, is self-contained, and the manipulation of said clamps is all that is necessary to secure the machine to or permit the removal of same from, the railway track. The screws 5 do not, in any way serve to attach the machine to the rail, they simply determine the lateral position of same relative to the rail.

Operation.--The operation of my machine 10 is substantially as follows: With each pair of clamps 2 positioned sufficiently far apart to permit the passage of the ball of the rail between them, the machine bed 1 is placed upon the rail in the position shown in Fig. 15 4, and the proper lateral adjustment of said bed is then secured by means of the screws 5. Clamps 2 are then tightened up so that they firmly engage the rail 3. When the machine is in the starting position, sleeve 33 20 is at the point upon the guide 34 indicated at A in Fig. 9, in which position the milling-cutter is held out of operative contact with the rail through the medium of the thickened end of the miller guide. The clutch- 25 members 13 and 14 are engaged. Now, when the machine is operated, by means of the cranks 23, carriage 8 travels in the direction indicated by said arrows. When sleeve 33 reaches position B, the milling-cutter is 30 working at its full depth of cut, and continues so to operate until it reaches position C, at which point, the profile of guide-strip 34 causes the cutter to move outwardly, against the action of spring 37, and when 35 said cutter reaches position C, it is fully out of operative contact with the rail, and the milling operation is completed. The guide-strip 34 may be turned end-for-end when necessary. In order to permit the quick re- 40 turn of the carriage to the starting position, clutch members are now disengaged, which will permit the carriage to be pushed quickly backward, without loss of time to the starting position. It will be understood that this 45 clutch provision obviates the necessity of working the carriage backward by means of the handles 23, which would be a slow process.

I claim:

50 1. In a milling machine, a bed arranged to be secured to a railway rail, a carriage arranged to travel upon said bed, a milling-cutter mounted in said carriage operable to remove a portion of the head of said rail, and a guide for said milling-cutter arranged to automatically define the operation of said milling-cutter upon said rail.

55 2. In a milling machine, a bed arranged to be secured to and to extend longitudinally of a railway-rail, means for adjusting said bed laterally upon said rail, a carriage mounted upon said bed and adapted to travel longitudinally thereof, a milling-cutter mounted upon said carriage operable to 60 remove a portion of the head of said rail,

and means arranged to automatically define the operation of said cutter upon said rail.

3. In a milling machine, a bed arranged to be secured to and to extend longitudinally of a railway-rail, a carriage arranged to 70 travel upon said bed longitudinally of said rail, means for causing said travel, an arm swingingly mounted upon said carriage, a milling-cutter carried by said arm, operable to remove a portion of the head of said rail, 75 and adapted to be operated by said carriage-operating means, and means arranged to automatically define the profile and longitudinal extent of the operation of said cutter upon said rail-head. 80

4. In a milling machine, a bed arranged to be secured to a railway-rail, a rack secured to said bed, a carriage arranged to travel upon said bed, a pinion revolvably mounted in said carriage engaging said rack, means 85 for revolving said pinion to cause said travel of said carriage, a milling-cutter yieldably mounted upon said carriage operable to remove a portion of the head of said rail, and means arranged to automatically act upon 90 said cutter in respect to said yieldability for the purpose of defining the action of said cutter upon said rail-head.

5. In a milling machine, a bed arranged to be secured to a railway rail and to extend 95 longitudinally thereof, means for causing and securing the lateral adjustment of said bed upon said rail, a carriage-rail upon said bed, a carriage arranged to travel upon said carriage-rail, means operable to cause said 100 travel, a milling-cutter yieldably mounted upon said carriage, operable to remove a portion of the head of said rail, and means arranged to cooperate with said cutter in respect to said yieldability, for the purpose 105 of defining the action of said cutter upon said head.

6. In a milling machine, a bed arranged to be secured to a railway-rail, and to be adjustable laterally thereon, means for causing 110 said adjustment, a rack secured to said bed, a carriage arranged to travel upon said bed, a feed-shaft mounted in said carriage, a pinion secured to said shaft and meshing with said rack, a worm-wheel revolvably mounted upon said feed-shaft and provided with a clutch-member, a clutch member feathered to said shaft adapted to engage the clutch-member upon said wheel for the purpose or revolving said shaft and the thereto- 115 attached pinion, a power-transmitting shaft carried by said carriage, a worm secured to said transmitting shaft and meshing with said worm-wheel, means operable to drive said power-transmitting shaft, a milling- 120 cutter carried by said carriage adapted to operate upon the head of said railway rail, and means transmitting motion from said transmitting-shaft to said milling-cutter. 125

7. In a milling machine, a bed arranged to 130

- be secured to a railway-rail, and to be adjustable laterally thereon, means for effecting said adjustment, a rack secured to said bed, a carriage arranged to travel upon said bed, a feed-shaft revolvably mounted in said carriage, a pinion secured to said shaft meshing with said rack and adapted to cause said travel of said carriage, a worm-wheel revolvably mounted upon said feed-shaft and provided with a clutch-member, a co-operating clutch-member feathered to said shaft and arranged to engage said wheel-member, for the purpose of causing the revolution of said feed-shaft and the thereto-attached pinion, a power-transmitting shaft carried by said carriage, means operable to drive said last-mentioned shaft, a worm keyed to said transmitting shaft and meshing with said worm-wheel, a spur-pinion also keyed to said transmitting shaft, an arm swingingly mounted upon said transmitting shaft, there being an eye at the free end of said arm, an arbor revolvably mounted in said arm, means transmitting motion from said transmitting shaft to said arbor, a milling-tool secured to said arbor and arranged to mill the head of said railway-rail, a bolt attached to said carriage and extending through said eye, a nut upon the outer end of said bolt, and a spring interposed between said nut and said arm for the purpose of yieldably holding said milling-cutter to its work.
8. In a milling machine a bed arranged to be secured to a railway-rail and to be adjustable laterally thereon, means for effecting and securing said adjustment, a rack secured to said bed, a carriage arranged to travel upon said bed, a feed-shaft revolvably mounted in said carriage, a pinion secured to said shaft meshing with said rack and adapted to cause said travel of said carriage, a worm-wheel revolvably mounted upon said feed-shaft and provided with a clutch-member, a co-operating clutch-member feathered to said shaft and arranged to engage said wheel-member, for the purpose of causing the revolution of said feed-shaft and the thereto-attached pinion, a power-transmitting shaft carried by said carriage, means operable to drive said last-mentioned shaft, a worm keyed to said transmitting shaft and meshing with said worm-wheel, a pinion also secured to said transmission shaft, an arm swingingly mounted upon said transmission-shaft, an arbor revolvably mounted in said arm and provided with a guide-section or sleeve, a milling-guide secured to said bed, and adapted for the impingement of said guide-sleeve, yieldable means arranged to hold said guide-sleeve in contact with said milling-guide, a milling-tool secured to said arbor arranged to mill the head of said rail, and means transmitting motion from said transmission shaft to said arbor and the milling-cutter carried thereby.

In testimony whereof I affix my signature in presence of two witnesses.

THOMAS F. HILLIARD.
